UNITED STATES PATENT OFFICE.

BAXTER R. PALLARDY, OF ST. LOUIS, MISSOURI.

FLASH-LIGHT SIGN.

Application filed December 16, 1921. Serial No. 522,733.

To all whom it may concern:

Be it known that I, BAXTER R. PALLARDY, a citizen of the United States, residing at St. Louis, Missouri, have invented a new and useful Flash-Light Sign, of which the following is a specification.

This invention relates to flash light signs.

An object of the invention is to provide a novel and improved flash light sign having an electric circuit that is opened and closed by a switch under control of the belt of an automotive engine.

Other objects will appear from the following description, reference being made to the accompanying drawing, in which—

Fig. 1 is a view showing my invention applied to an automobile.

Fig. 2 is an enlarged view showing the electric switch under control of the fan belt. Fig. 3 is an enlarged sectional view showing a form of switch adapted for use as a part of the invention.

Fig. 4 is a sectional view on the line 4—4 of Fig. 3.

In the embodiment of the invention shown an appropriate sign or signal 1 is supported by the automobile, and a lamp 2 is arranged to illuminate the sign. An electric circuit from the battery or other source of energy supplies the electric current for the lamp.

One of the wires 3 of the electric circuit leads to a binding post 4 on an insulation support 5 supported near the fan belt 6. The connecting wire 7 from the lamp leads to a binding post 8 movably supported in the insulation support 5 and having an arm 9 adapted to be moved into and out of contact with the binding post 4 to close and to open the circuit. The contact member 8 extends through an opening 10 in a switch lever 11 which is pivotally supported upon a pin 12 in the insulation support 5. The lever 11 prevents the contact member 8 from becoming disconnected from the support.

Movement of the lever 11 in a direction away from the support 5 will move the contact member 8 so as to contact the arm 9 thereof with the binding post 4; and movement of the lever 11 toward the support 5 will move the contact member in a direction to break the circuit. A spring 13 located between the support 5 and the lever 11 actuates the lever in a direction away from the support 5, thereby moving the contact member in a direction to close the circuit.

A roller 14 on the end of the lever 11

operates against the fan belt 6, permitting the spring 13 to hold the lever 11 in position to close the circuit. The fan belt is formed with a thick or raised portion 15 which when operating against the roller 14 presses the lever 11 toward the support 5 a distance sufficient to move the contact member 8 out of contact with the binding post 4 to break the circuit.

As the fan belt is in continuous operation when the engine is running it is perfectly plain that the circuit is alternately opened and closed automatically and as an incident to the running of the engine. The flash light sign is thereby operated intermittently, making an attractive display plainly observable.

An improved sign of this construction and arrangement is of inexpensive construction and may be easily mounted upon the automobile from which it is to be shown. The sign is automatically flashed on and off as an incident to the operation of the engine whether the automobile is in motion or not. It is apparent that other equivalent devices may be employed to operate the switch without departure from the nature and principle of the invention. Accordingly, I do not restrict myself unessentially or to the exact construction and arrangement shown, but what I claim and desire to secure by Letters Patent, is:—

1. In a device of the character described, a support having an angular recess therein, a contact member in the support intersecting one end of said recess, an electric circuit wire connected with said contact member, an angular contact member movable back and forth in said recess into and out of contact with the first contact member, an electric circuit wire connected with the angular contact member, a lever engaging said angular contact member and having one end pivoted in said recess, and a spring on the support for actuating said lever in a direction to move the angular contact member toward the first contact member.

2. In a device of the character described, a support having an angular recess therein, a contact member in the support intersecting one end of said recess, an electric circuit wire connected with said contact member, an angular contact member movable back and forth in said recess into and out of contact with the first contact member, an electric circuit wire connected with the angular

contact member, a lever engaging said angular contact member and having one end pivoted in said recess, a spring on the support for actuating said lever in a direction to move the angular contact member toward the first contact member, and a device moving continuously in one direction when in operation for operating said lever in opposition to said spring to move said angular contact member out of contact with said first contact member.

3. In a device of the character described, a support having an angular recess therein, a stationary contact member in the support intersecting said recess, an electric circuit

wire connected with said contact member, a movable contact member in said angular recess movable into and out of contact with the stationary contact member, an electric circuit wire connected with the movable contact member, a lever pivoted to said support and engaging said movable contact member and preventing said movable contact member from working out of said support, and a spring in connection with said support for actuating said lever in a direction to move said movable contact member into contact with said stationary contact member. 20 25

BAXTER R. PALLARDY.
